UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

PLATE-CLAMP.

1,259,976.

Specification of Letters Patent. Patented Mar. 19, 1918.

Application filed November 29, 1916. Serial No. 134,193.

To all whom it may concern:

Be it known that I, SAMUEL G. Goss, a citizen of the United States, and a resident of Glencoe, in the county of Cook and State 5 of Illinois, have invented certain new and useful Improvements in Plate-Clamps, of which the following is a specification, reference being had to the accompanying drawings.

10 My invention relates to plate clamps of a type adapted for securing curved printing plates upon a plate cylinder, and the principal object of my invention is the production of a new and improved form of clamp by 15 which a system of marking shall be provided by reason of which the assembly of the several printed and folded products in proper rotation for the formation of a book may be expedited. To this end it is the object 20 of my invention to provide a plurality of plate clamp members any desired one of which members may be used in the appropriate location in the production of any given section of the book whereby in the 25 completely assembled set of sections for the book the presence of a complete line of distinguishing marks indicates a proper arrangement of the sections, while a break in the line of marks indicates an incorrect arrangement. It is another object of my 30 invention to improve devices of this type in sundry details hereinafter pointed out. The preferred means by which I have accomplished my several objects are illustrated 35 in the drawings and are hereinafter specifically described. That which I believe to be new and desire to cover by this application is set forth in the claims.

In the drawings:—

40 Figure 1 is a side view of a portion of a plate cylinder provided with one of my improved clamps;

Fig. 2 is a vertical cross-section taken substantially on line 2—2 of Fig. 1;

45 Fig. 3 is an enlarged detail, being substantially a section taken on line 3—3 of Fig. 1;

Figs. 4, 5, 6 and 7 illustrate the four forms of plate clamp members employed in accomplishing the desired system of marking;

Fig. 8 illustrates a form of wrench for use with the clamp of Fig. 7;

Fig. 9 illustrates a set of book sections

arranged in proper order showing by the alined distinguishing marks that the sections have the proper arrangement; and 55

Fig. 10 is a diagrammatic view showing one of the clamp members in solid lines and illustrating in dotted lines the relative positions which the other clamp members may 60 be given for producing the distinguishing mark at the desired point circumferentially of the cylinder.

Referring to the several figures of the drawings, in which corresponding parts are 65 indicated by the same reference characters,—

15 indicates a plate cylinder mounted upon a shaft 16. The cylinder 15 is provided at an appropriate point with a fixed 70 clamping ring 17 extending circumferentially about the cylinder adapted to hold in position the inner end of a plate such as the plate 18. Plate clamps 19 slidably mounted in suitable grooves in the cylinder 75 15 serve to hold in position the outer end of the plate 18 and the inner end of a plate 20, the outer end of which is held in position by a plurality of plate clamps 21 which are adjustably mounted relative to a head 80 22 which is adapted to be adjusted as desired longitudinally of the cylinder for tightening the clamps 21 against the plate 20 whereby the plates 20 and 18 are very firmly secured in position. Upon the opposite side of the cylinder circumferentially thereof, other plates 23 are secured in position in like manner, as will be readily understood. Ribs 24 fixed upon the cylinder 85 serve to hold the plates in position circumferentially thereof.

90 Each of the intermediate clamps 19 comprises a head portion 25 and a base portion 26 connected together by means of a suitable screw 27. In the construction shown in Fig. 95 3, the connecting screw 27 is provided with a lug 28 which extends type high above the face of the clamp whereby it is adapted to receive ink which during the impression is deposited upon the web. The screw 27 is 100 adapted to be turned by the use of a suitable wrench such as the wrench 29 illustrated in Fig. 8.

105 In the use of my improved system, a section of a complete book will be printed with a set of clamps as illustrated in Figs. 1 and

CHAPTER 10: THE FUTURE OF THE INDUSTRY

2. Another section will then be printed with the head 25 removed from the clamp as shown in Fig. 3 and with a head 30 substituted therefor, such head 30 being provided
5 with a lug 31 type high thereon at one side of the screw by which the head 30 and the base 26 are connected. Another section of the complete book will be printed with a head 32 substituted for the head 25, the head 32 being provided with a lug 33 which also is type high. Another section will be printed with a head 34 in position provided with a type-high lug 35. Still other sections are printed with the heads 30, 32 and 34 in
10 the reverse position, as indicated in Fig. 10, all of such changes being made in connection with the clamp shown in Fig. 3. Seven additional sections each with its own distinctive marking may then be printed in appropriate order with the heads 30—32—34 substituted successively for the heads 25 of the other intermediate clamps 19 by which the plate 18 is held in position, the arrangement and construction illustrated being capable of producing twenty-eight differently-marked sections or products. It will be understood that if desired while the plates 18 and 20 upon one side of the cylinder are producing a given section with its appropriate marking, the plates 23 upon the opposite side of the cylinder may be producing a different section with its appropriate marking.

It will be understood that if desired two of the clamps 19 might be provided with printing lugs, in case two products should be produced by a single plate. Indeed, it will be appreciated that many changes may be introduced from the precise form and arrangement illustrated in the drawings without departing from the spirit of my invention.

So far as I am aware, I am the first in the art to provide printing lugs upon the intermediate plate clamps for giving the various sections distinctive marks as above described, and my claims are, therefore, to be construed accordingly.

What I claim as my invention and desire to secure by Letters Patent, is—

1. The combination of a plate clamp with a printing member carried thereby adapted to mark a printed product at the line of fold between pages in accordance with a pre-determined plan of distinctive marking.

2. The combination of a cylinder, and a plurality of plate clamp members slidably mounted on said cylinder, comprising a printing member adapted to be positioned in a plurality of different positions for marking different printed products in a plurality of different relative positions in accordance with a predetermined plan of distinctive marking.

3. The combination of a cylinder, and a plurality of plate clamp members slidably mounted on said cylinder, one or more of said clamp members comprising a printing member adapted to be positioned in any of a plurality of positions relative to the center of the clamp for marking different printed products in a plurality of different relative positions in accordance with a predetermined plan of distinctive marking. 65 70

4. The combination of a plate clamp base, 75
a plurality of head members, and means for
securing any one of said head members as
desired in position upon said base, said head
members being provided with printing mem-
bers differently arranged thereon relative to
the position of the base, whereby said print-
ing members are adapted to mark different
printed products in different ways in ac-
cordance with a predetermined plan of dis-
tinctive marking. 80 85

5. The combination of a plate clamp base, a head member, means for securing said head member in either of two reversed positions upon said base, and a printing member carried by said head member at one side of said 90 securing means.

6. The combination of a plate clamp, and a printing lug adjustably connected thereto adapted to mark different printed products in a plurality of different relative positions. 95

SAMUEL G. GOSS.
